UNITED STATES PATENT OFFICE

EMANUEL PAPPERT, OF NEW YORK, N. Y.

DESIGN FOR A SPECTACLE FRAME

Application filed November 2, 1929. Serial No. 33,277. Term of patent 3½ years.

To all whom it may concern:

Be it known that I, EMANUEL PAPPERT, a citizen of the United States, residing at the city and State of New York, county of Bronx, have invented a new, original, and ornamental Design for Spectacle Frames, of which the following is a specification, reference being had to the accompanying drawing, forming part thereof.

The figure is a perspective view of a spectacle frame embodying my new design.

I claim:

The ornamental design for a spectacle frame as shown.

EMANUEL PAPPERT.
